UNITED STATES PATENT OFFICE.

ALBERT M. OSLOCK, OF ELGIN, ILLINOIS, ASSIGNOR TO N. W. CHURCH, OF LOS ANGELES, CALIFORNIA.

ODOMETER CONSTRUCTION.

Application filed November 23, 1922. Serial No. 302,735.

To all whom it may concern:

Be it known that I, ALBERT M. OSLOCK, a citizen of the United States, residing at Elgin, in the county of Kane and State of Illinois, have invented certain new and useful Improvements in Odometer Constructions, of which the following is a specification.

This invention relates to improvements in odometer construction and has for an object to provide a new and improved form of odometer in which the movement of a rotating element, or the like may be efficiently and satisfactorily transmitted to and registered by the indicating elements.

Another object consists in the specific arrangement and construction of the odometer and allied elements.

Another object consists in the means to set the reset or trip odometer. These and other objects will be more fully described and disclosed in the following specification and shown in the accompanying drawings in which—

25 Figure 1 is a front elevation of an odometer, comprising total mileage and trip sections, a portion of the reset mechanism being shown in section for clearness;

Fig. 2 is a transverse section along the line 30 2—2 of Fig. 1;

Fig. 3 is a vertical section along the line 3—3 of Fig. 1.

Fig. 4 is a transverse section taken along the line 4—4 of Fig. 3.

35 Fig. 5 is a side elevation of a gear secured to the first wheel of the total mileage section;

Fig. 6 is a front elevation of the driving mechanism, portions of the same being 40 shown in section for clearness;

Fig. 7 is a vertical section, taken along the line 7—7 of Fig. 1; and

Fig. 8 is a horizontal section taken along the line 8—8 of Fig. 7.

45 Like numerals refer to like elements throughout the drawings in which 10 designates the back wall or frame of the instrument, which projects outwardly from the bearing brackets 11—12, see Fig. 1, and a 50 central bracket or pedestal 13, see Figs. 1 and 7. Extending between and mounted in

the end bracket 11 and center bracket 13 is a shaft 15 held against removal or accidental displacement by means of the screw head 16, see Fig. 1. Mounted on the shaft 55 15 is the hollow sleeve 18 upon which are mounted the unit mileage indicator wheel 19 and a plurality of additional indicator wheels indicated by numerals 20. Secured to the sleeve 18 outwardly of the indicator 60 wheels 20 is the collar 21, see Figs. 2 and 3, for example, this collar being provided with the slotted projection 21^a and the upstruck lug or tongue 21^b, the latter fitting a keyway 15^a in the sleeve 18. Extending through 65 a threaded aperture in the bracket 11, is the adjusting screw 23 having an eccentric portion 23^a fitting the slot in the collar 21. It will be apparent that rotation of the screw 23 will operate to partially rotate the collar 70 21 and sleeve 18. This partial rotation will be communicated to the mileage wheels 20 through carry-over mechanism, not shown. The purpose of this construction is to permit the alinement of the numerals on the 75 total mileage indicator with those of the trip indicating wheels, not yet described, where inaccuracies in manufacture result in a partial misalinement. The shaft 15 is recessed at 15^b at one extremity and a coil 80 spring 25 is mounted therein.

The sleeve 18 is provided with a collar or washer 26 at its inner extremity. Secured between this collar 26 and the bracket 13 is the gear member 27 having a toothed flange 85 27^a at one side and inclined arms 27^b toothed or corrugated at 27^c at their extremities at the other side. These toothed extremities 27^c mesh with and engage teeth 19^a at one side of the unit wheel 19 in a manner similar 90 to that shown in Fig. 4.

Bearings 28 and 29 extend upwardly from the wall 10 at either side of the bracket 13 and in these bearings is journaled a shaft 30, see Figs. 1, 7 and 8. Carried by this shaft 95 30 outside the bearing 28 is the worm gear 31 in mesh with and actuated by the worm 32, carried on shaft 33, which latter shaft is also provided with the worm gear 34 actuated by the worm 35, see Fig. 1 for example. 100 This worm 35 is carried upon the shaft 36 which also carries the worm gear 37, which

is in mesh with a worm 38, carried upon the main drive shaft 39, which is seated in the sleeve 40, extending through and engaged by the ring flange 41 of the base 10, see Fig. 6. 5 Journaled in the bracket 13 is the pinion shaft 43, carrying at one side of the bracket the pinion 44, and at the other side of the bracket the pinion 45. Pinion 44 meshes with a gear 45^a carried upon a hub 46, which 10 is carried by and secured to the shaft 30. The rotatable disk 47 is also carried by the hub 46, this disk being cut away at one side and provided with a pair of teeth 47^a, meshable at each revolution with teeth on pinion 15 45, see Figs. 7 and 8, for example. Pinion 45 is in mesh with teeth 27^a of the gear member 27 and it will be apparent that disk gear 47, when continuously rotated by the shaft 30 will on every revolution advance or 20 move the pinion 45 a portion of a revolution, which movement will be transmitted to gear 27. By properly constructing the members, this movement will correspond to one division of the indicator wheel 19, the same being usually divided into ten indications representing one to ten miles, the disk 47 making one rotation per mile of travel on the vehicle on which it is attached. Carry-over mechanism of any suitable construction may 25 30 be mounted upon the sleeve 18 between the unit wheel 19 and the adjacent indicator wheel 20, also between each of the succeeding indicator wheels to transmit, in well known manner, in ratio of one to ten, the 35 revolutions of the adjacent wheel.

A shaft 50 is provided for the trip mileage group, this shaft 50 having an extension 50^a fitting into the recess 15^b, of shaft 15 and being provided with a roughened or 40 toothed portion 50^b upon which is forced the hub of the gear 51. Mounted upon the shaft 50 also is the connector 52 having a hub forced into engagement with a toothed or roughened portion 50^c of a shaft 50 and 45 provided with teeth 52^a or the like, at its extremities, see Figs. 3 and 4. This connector 52 meshes with internal teeth 54^a of the tenths indicator wheel 55, which is rotatably mounted upon the sleeve 56, which in turn 50 is mounted on shaft 50. Sleeve 56 is collared or flanged at its extremities 56^a, 56^b, see Fig. 3, and rotatably mounted upon it are the additional trip indicator wheels 58, to which motion is successively applied by 55 suitable carry-over mechanism from the tenths wheel 55 in well known manner. The flange 56^a is extended for engagement with a stud or pin 57 by projecting outwardly from the bracket 13, see Figs. 1 and 7, this 60 engagement preventing rotation of the sleeve 56.

The shaft 50 is provided with an extension 50^d extending through the bracket 12 and provided with tongues or lugs 50^e. 65 Shaft 50 is also provided with a round tip

50^f. Mounted upon the extension 50^d adjacent the extremity thereof is the bevel gear 60 having the slots 60^a into which fit lugs or tongues 50^e struck-up from the extension 50^d. The bracket 12 is chambered at 12^a 70 to accommodate the stem of the gear 60. A casing 70 provided with a split collar 70^a is attached by clamping the latter to the boss 12^b of bracket 12 the clamping screws 71 being provided for that purpose, see Fig. 1. Journaled in this casing 70 is the shiftable stem 72 having the knurled cap 73 at its outer extremity. Secured to the stem 72 is bevel gear 74 meshable with the gear 60, as shown in Fig. 1. Outwardly of the gear 74 is the cam extension 72^a of stem 72, having a groove 72^b therein into which projects tip 50^f of extension 50^d when the gears are in mesh, this serving to hold the stem 72 in position wherein the gears will mesh. The cam 72^a is tapered from the grooves 72^b towards its outer extremity. 75 80 85

When the stem 72 is moved to position shown in Fig. 1, the cam extension 72^a shifts the shaft 50 toward the left against the action of spring 25, at the same time moving gear 51 out of mesh with pinion 44. Tip 50^f registering with groove 72^b is held in such register by means of the spring 25, which, as stated, holds stem 73 in upward 90 position, as viewed in Fig. 1, wherein the shaft 50 may be rotated by means of the stem 72 for setting of the trip indicator wheels, as desired. When such setting has been accomplished, the stem 72 may be re-shifted in mesh with gears 60 and 74 permitting mesh of gear 51 with pinion 44. This will permit mechanical drive of the trip odometer through the mechanism previously 100 described. 105

This reset mechanism provides a quick and satisfactory means for setting or resetting the trip odometer which is especially desirable under present day conditions where touring is generally undertaken with the assistance of route books identifying landmarks by mileage indication. 110

It will be obvious that my invention can be modified or altered and I do not wish to be restricted to the form shown and described except as defined in the appended claims. 115

What I claim is—

1. In combination, a normally stationary support, a plurality of indicator wheels rotatably mounted on said support, and means to rotatably adjust said support and indicator wheels to properly align said wheels as a unit relative to a window or the like. 120

2. In combination, a stationary support, a plurality of indicator wheels rotatably mounted on said support, means to partially rotate said support and indicator wheels for adjustment, said means comprising a 125 130

member carried by said support, and a screw member having an eccentric portion engaging said member.

3. In combination, a stationary support, 5 a plurality of indicator wheels rotatably mounted on said support, means to partially rotate said shaft and indicator wheels for

adjustment, said means comprising a slotted collar carried by said support, and a screw member having an eccentric portion engaging the slot in said collar.

In testimony whereof, I have subscribed my name.

ALBERT M. OSLOCK.

10

Certificate of Correction.

It is hereby certified that in Letters Patent No. 1,522,646, granted January 13, 1925, upon the application of Albert M. Oslock, of Elgin, Illinois, for an improvement in "Odometer Constructions," an error appears in the printed specification requiring correction as follows: Page 3, line 7, claim 3, for the word "shaft" read *support*; and that the said Letters Patent should be read with this correction therein that the same may conform to the record of the case in the Patent Office.

Signed and sealed this 21st day of April, A. D. 1925.

[SEAL.]

KARL FENNING,
Acting Commissioner of Patents.
